Primary Examiner — Rosemary K Tarcza(74) *Attorney, Agent, or Firm* — Banner & Witcoff, Ltd.(57) **CLAIM**

The ornamental design for a battery, as shown and described.

DESCRIPTION

FIG. 1 is a top, front, right perspective view of the claimed design for a battery;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is an enlarged fragmentary view of FIG. 1, wherein some broken line subject matter is omitted to enhance clarity.

The broken lines immediately adjacent to the shaded area depict boundaries of the claimed design and form no part thereof. The broken lines showing the remainder of the battery depict environmental structure and form no part of the claimed design. Portions of the battery not shown in the drawing form no part of the claimed design.
